UNITED STATES PATENT OFFICE

92,629

DESIGN FOR A COCKTAIL MIXER

Morris B. Solomon, New York, N. Y.

Application April 24, 1934, Serial No. 51,502

Term of patent 3½ years

To all whom it may concern:

Be it known that I, MORRIS B. SOLOMON, a citizen of the United States of America, and residing at New York city, in the county of New York, and State of New York, have invented a new, original, and ornamental Design for a Cocktail Mixer, of which the following is a specification, reference being had to the accompanying drawing, forming part thereof.

I claim:

The ornamental design for a cocktail mixer substantially as shown.

MORRIS B. SOLOMON,
